CLAIM

The ornamental design for a backing plate for servomotor diaphragm, as shown.

DESCRIPTION

FIG. 1 is an end elevational view of a backing plate for servomotor diaphragm showing our new design;

FIG. 2 is a side elevational view thereof;

FIG. 3 is a front elevational view thereof; and

FIG. 4 is a cross-sectional view thereof taken along line 4—4 of FIG. 2.

FIG. 1

FIG. 4

FIG. 2

FIG. 3
